AKTIEBOLAGET BALTIC, OF SÖDERTELJE, SWEDEN, A CORPORATION OF SWEDEN.

REGULATING MEANS FOR CENTRIFUGAL LIQUID-SEPARATORS.

1,131,421.

Specification of Letters Patent.

Patented Mar. 9, 1915.

Application filed September 12, 1914. Serial No. 861,457.

To all whom it may concern:

Be it known that I, JOHANNES VALDEMAR MÄRTEN RISBERG, a subject of the King of Sweden, and resident of Badhusgatan 16, 5 Södertelje, in the Kingdom of Sweden, have invented certain new and useful Improvements in Regulating Means for Centrifugal Liquid-Separators, of which the following is a specification, reference being had there- 10 in to the accompanying drawing.

In centrifugal milk separators provided with a top plate means are used for regulating the proportions of the separated liquids, consisting of a regulating screw which is 15 provided with a passage and is located either in the top plate or in the wall of the drum and by means of which the discharging openings of the cream and of the skimmed milk respectively are adjusted. 20 Owing to the fact that the top plate is of a comparatively thin material, a regulating screw can be provided in the same only when a ring, disk or the like has been soldered or in any other manner fixed to the plate for 25 reinforcing the same. In the wall of the drum, on the other hand, which is of a thicker material, a regulating screw may be provided without the said wall being reinforced *i. e.* the screw may mesh directly with 30 the wall. For that reason the arrangement last mentioned is preferred by the manufacturers but involves the disadvantage of the skimmed milk leaving the drum at a point located at a greater distance from the 35 rotary axis of the drum than really is necessary, which increases the amount of power necessary for the rotating of the drum.

According to this invention the said disadvantage is removed by providing in a part 40 of the wall of the drum, which is located nearer to the rotary axis of the drum, one or more exit openings for the skimmed milk, which as to their width are so adapted that the greatest part of the skimmed milk, for 45 instance 75 to 80 per cent., passes through the said openings, while the rest passes through the regulating screw.

In the accompanying drawing Figure 1 is a vertical section partially a side view of a 50 centrifugal drum provided with a regulating device according to this invention. Fig. 2 shows in the same manner the top part of a centrifugal drum provided with a regulating screw of a different construction. Figs. 55 3 and 4 show in a side view and in an end

view respectively the regulating screw illustrated in Fig. 2. Figs. 5 and 6 show in a longitudinal section and in an end view a further form of the regulating screw.

The invention is shown adapted to a centrifugal apparatus provided with a center tube 1, a nut 2 meshing with the said tube, a top plate 3 and a hood 4.

5, Fig. 1, is a regulating screw of the construction hitherto used, which is located in 65 the wall of the drum, radially or substantially radially to the drum and provided with a longitudinal passage 6. The said screw is in engagement with the hood 4.

The cream passes through an opening 7 70 provided in the top plate 3. According to this invention an opening 8 (or a plurality of openings) is provided in the part of the hood 4, which is located nearest to the axis of the drum, which opening as to its width 75 and position is so adapted, that the main part of the skimmed milk passes through the same.

The regulation of the proportions of 80 skimmed milk and cream is effected by shifting the screw 5. By moving the regulating screw 5 outward a reduced quantity of cream will leave the separator and, vice versa, a greater quantity of cream is gained by moving the screw inward. By moving 85 the regulating screw to its outmost position the smallest possible quantity of cream will leave the drum, and the apparatus is so constructed that, when the screw is in its innermost position, the greatest quantity of cream 90 is gained, which on the whole is possible. Consequently, at the normal percentage of 95 cream only a small quantity of the skimmed milk will pass through the regulating screw. The greatest part of the skimmed milk passes through the opening 8 located near the axis of the drum, so that no power is lost unnecessarily for the ejecting of the skimmed milk.

The apparatus shown in Fig. 2 is constructed in the same manner as the apparatus shown in Fig. 1 but the regulating screw differs from the one shown in the figure last mentioned. The regulating screw 5 shown in Fig. 2 and in Figs. 3 and 4 is 100 provided with a slot 9 which divides the screw into two parts for the greater part of its length, leaving a bottom 9* undivided. The screw is so mounted in the drum, that the 105 said bottom 9* is turned inward toward the 110

axis of the drum and normally a part of the slot 9 is uncovered inside the wall of the drum, as shown in Fig. 2. The regulation by means of the screw shown in Figs. 2, 3 and 4 is effected, as understood without any explanations according to rules contrary to those stated above with relation to Fig. 1, so that the quantity of skimmed milk is increased, and the quantity of cream decreased, 10 if the screw is moved inward, and vice versa if the screw is moved outward. One of the advantages of the screw shown in Figs. 2, 3 and 4 consists in the same rules for the adjusting of the screw being applicable as for 15 the adjusting of the so called cream screw used of old, which screw is located in the exit opening for the cream and by means of which the quantity of cream is decreased as the screw is moved inward and vice versa, 20 which rule, so to say, has entered into the consciousness of all users of centrifugal apparatus of the old construction.

Fig. 4 shows a further form of the regulating screw to be used in the same manner 25 as the screw shown in Figs. 2 to 4 inclusive. The screw shown in Fig. 4 has a bore 10 from which a side slot 11 extends. Any number of slots 9 and 11 respectively may 30 evidently be used, and the construction of the regulating screw may be modified in many other respects as easily understood by those skilled in the art. The invention may

be applied to other centrifugal liquid separators than milk separators.

Having now described my invention, what 35 I claim as new and desire to secure by Letters Patent is:

1. For the regulating of the proportions of the separated liquids in centrifugal liquid separators the combination of a regulating 40 screw located in the wall of the drum and provided with a passage for the skimmed milk and an outlet opening for the greater quantity of the skimmed milk provided in the wall of the drum nearer to the axis of 45 the drum.

2. For the regulating of the proportions of the separated liquids in centrifugal liquid separators the combination of a regulating screw located substantially radially in the 50 wall of the drum and provided with a lateral outlet opening extending to the side of the screw which is located outside the wall of the drum, and an outlet opening for the greater quantity of the skimmed milk 55 provided in the wall of the drum nearer to the axis of the drum.

In witness whereof, I have hereunto signed my name in the presence of two subscribing witnesses.

JOHANNES VALDEMAR MÄRTEN RISBERG.
